UNITED STATES PATENT OFFICE.

VICTOR H. JENNINGS, OF WORCESTER, MASSACHUSETTS, ASSIGNOR TO MILLS WOVEN CARTRIDGE BELT CO., OF WORCESTER, MASSACHUSETTS, A CORPORATION OF MASSACHUSETTS.

BELT.

1,035,350.

Specification of Letters Patent. Patented Aug. 13, 1912.

Application filed December 5, 1910. Serial No. 595,773.

To all whom it may concern:

Be it known that I, VICTOR H. JENNINGS, a subject of the King of Great Britain, residing at Worcester, in the county of 5 Worcester and State of Massachusetts, have invented new and useful Improvements in Belts, of which the following is a specification.

This invention relates to improvements in 10 belts, and particularly to a woven fabric belt having a portion of its extent of a different thickness than the other portion thereof, and the object is to provide a belt of this character having a smooth, continuous 15 and unbroken surface on its outer face, and an improved method of weaving the same.

With the above object in view, the invention 20 consists in the novel features of construction hereinafter fully described, particularly pointed out in the claims, and clearly illustrated by the accompanying drawing, in which—

Figure 1 is an edge view of a portion of 25 a belt woven in accordance with my invention; Fig. 2, a face view of a portion of the belt showing the inner face before cutting off the floating threads, and Fig. 3, a diagrammatic view showing the method of 30 weaving the belt.

The invention relates to belts or other articles of woven fabric where it is desired 35 to form the same of two different thicknesses. This may be done by disassociating the threads of one or more plies, while the other plies are being woven into a solid fabric. For example, there may be two plies running 40 one above the other and being bound by the loom into a single compact fabric. One of these plies produces the face of the belt or 45 other article, and the other ply the back. It is ordinarily desired that the face of the belt or fabric shall be as smooth as possible, producing a continuous and unbroken surface. It is possible at the desired point to 50 drop out the threads of the back ply and continue the weaving only of the front ply, but in practice this does not produce the smoothness of appearance desired on the front face of the belt. My invention enables me to produce such desired smooth 55 surface by substituting, in the process of

weaving, the back warp for the front warp at the point where the thinner portion of the fabric begins.

In carrying out my invention, I weave the 55 desired length of fabric having the greatest number of plies. I then pass the back or lower warp 1 through the front or upper warp 2 at the point A, and weave a number 60 of picks in the form of a tubular section B, the front, or upper warp 2, or top wall of the pocket, if a pocket is being woven, becoming the lower ply of the tubular section, and the lower warp 1 or back wall of the 65 pocket, forming the upper ply of the tubular section. This is done to enable me to secure a neat finish at the point where the fabric is reduced from a greater number of 70 plies to a less number.

After the necessary number of picks of 75 the tubular section have been woven, I drop the threads of the upper warp 2 which forms the lower ply of the tubular section, and weave the back or lower warp 1, which forms 80 the upper ply of the tubular section, in the form of a single-ply fabric 3.

The reason for substituting the lower 85 warp or back wall of the fabric, or pocket, for the upper warp or front wall, to produce the thinner portion, is that the warp which forms the back wall usually carries a greater amount of tension in the loom, thus giving a much stronger and firmer fabric than is obtainable from the warp which 90 forms the upper wall of the pocket.

I have illustrated a belt having pockets, but my invention is not limited thereto, as plain belts of two thicknesses, that is belts 95 without pockets, may also be woven in accordance therewith. Where pockets are provided they may be either with or without integrally woven partitions. Where pockets are woven having partitions, as illustrated, in passing from the weaving thereof to the single-ply portion, the threads of the partition or center-wall 4 are carried through the tubular section as floating or dead threads, that is, threads that are not interwoven with surrounding threads, and 100 these threads are dropped with the threads comprising the lower ply of the tubular section, and in the finishing process they are cut off with the latter.

After weaving the desired number of pockets, I may weave a few picks of tubular section, using the upper warp or top-ply of the pocket for the upper ply of the tubular section, and the lower warp or back-ply of the pocket for the lower-ply thereof, the threads of the partition warp being carried as dead threads. After the necessary length of tubular section has been woven, I may raise the threads of the upper warp and partition warp and weave as a single ply, the lower warp, or back wall of the pocket only.

It should be noted that, as any of the single plies of the fabric is much lighter than the portion of the belt composed of several plies, it may be desirable to give additional stiffness thereto, and for this purpose I sometimes employ in that portion of the fabric which consists of a single ply, a filling or weft thread of much heavier or harder yarn than the filling used in forming the portion of the belt composed of several plies, or I may make the warp threads which form the partition wall of the pocket of yarn much heavier or harder than the yarn composing the warp of the other plies of the fabric, and this partition warp may then be used to produce the single fabric, the upper and lower warps on either side of it being dropped. In following this method, I would weave the same as hereinbefore described until I conclude the weaving of the tubular section, then that part of the center warp which has been carried as dead threads through the tubular section is entered by the weft, which begins to form from it, the single ply fabric, while, at the same time, the lower and upper warps are dropped and their threads carried as floating threads to be cut off in the finishing of the fabric.

The tubular section produced in any of the methods of weaving described, is formed for the purpose of affording a means of neatly finishing the belt at the point where the floating threads are cut away. These floating threads having been sheared off where they project from the tubular section, the latter may then be turned inward upon itself and stitched or otherwise fastened. This conceals all loose threads or raw edges and prevents unraveling.

The production of the tubular section may not always be necessary, in which case it may be omitted, and the threads of the dropped warp sheared away close to the point at which they emerge from the main fabric.

Having thus fully described my invention, what I claim as new and desire to secure by Letters Patent of the United States, is:

1. A multiply fabric of different thicknesses having the thinner portion formed of the lower or back warp of the thick portion and extended as a continuation of the front

or upper warp of the thick portion by passing said lower warp through the upper warp in the process of weaving.

2. A multiply fabric consisting of two solid portions, one of lesser plies than the other, and intermediate between them a tubular section, the edge of which is united to the fabric proper after cutting away the threads of the ply or plies not used in weaving the thinner portion of the fabric, which are carried as floating threads.

3. A woven fabric of different thicknesses, the thinner portion of which is formed by carrying the threads of one or more plies forming the thicker portion as floating threads and severing the same from the fabric, said fabric being formed with a tubular portion at the juncture of the thin and thick portions, the edge of which is turned in and united to the fabric after the floating threads are cut off.

4. The improved method of weaving a fabric of different thicknesses, consisting in weaving a portion having the greater number of plies, then weaving a tubular section, then weaving the portion of the fabric containing the lesser number of plies, and finishing the fabric by cutting off the threads not used in weaving the thinner portion and uniting the tubular section at its open edge to the fabric.

5. The improved method of weaving a fabric of different thicknesses, consisting in weaving a portion having the greater number of plies, then passing the back warp through the upper warp, and then weaving a tubular section, then weaving the portion of the fabric containing the lesser number of plies using said back warp, and finishing the fabric by cutting off the threads not used in weaving the thinner portion and uniting the tubular section at its open edge to the fabric.

6. The improved method of weaving a fabric of different thicknesses, consisting in weaving a portion containing the greater number of plies, terminating in a tubular section, then weaving the thinner portion as a continuation of one of the walls of the tubular portion, and finishing by cutting off the threads not used in weaving the thinner portion at the end of the other wall of the tubular portion and uniting said wall at its open end to the fabric.

7. The improved method of weaving a fabric of different thicknesses, consisting in weaving a portion containing the greater number of plies, then weaving a tubular portion with the use of some of the plies forming the thick portion and carrying the threads of the other plies therethrough as dead threads, then weaving the thin portion with the threads forming a ply or plies of the thick portion, and then finishing by cutting out the threads not used in weaving the

thin portion and uniting the open edge of the tubular portion to the fabric.

8. The improved method of weaving a fabric having different thicknesses, consisting in weaving the portion having the greater number of plies, then weaving the thinner portion by extending the intermediate ply or plies and weaving the other ply or plies on each side thereof at the juncture of the thicker portion to form tubular por-

tions, and finishing by severing the threads not used in weaving the thinner portion and then uniting the open ends of the tubular portions to the fabric.

In testimony whereof I affix my signature ¹⁵ in the presence of two witnesses.
